UNITED STATES PATENT OFFICE.

WILLIAM J. BUTLER, OF CRANSTON, RHODE ISLAND, ASSIGNOR TO HENRY LEDERER & BRO. INC., OF PROVIDENCE, RHODE ISLAND, A CORPORATION OF RHODE ISLAND.

DESIGN FOR A POCKET CIGAR LIGHTER.

Application filed October 6, 1927. Serial No. 23,653. Term of patent 14 years.

To all whom it may concern:

Be it known that I, WILLIAM J. BUTLER, a citizen of the United States, residing in the city of Cranston, county of Providence, and State of Rhode Island, have invented a new, original, and ornamental Design for a Pocket Cigar Lighter, of which the following is a specification, reference being had to the accompanying drawing, forming a part thereof.

I claim:

The ornamental design for a pocket cigar lighter, substantially as shown.

WILLIAM J. BUTLER.
